DESIGN FOR A CAMERA SUPPORT

Neil J. Creedon, Glens Falls, N. Y.

Application May 28, 1945, Serial No. 119,768

Term of patent 14 years

(Cl. D61—1)

To all whom it may concern:

Be it known that I, Neil J. Creedon, a citizen of the United States, residing at Glens Falls, in the county of Warren and State of New York, have invented a new, original, and ornamental Design for a Camera Support, of which the following is a specification, reference being had to the accompanying drawing, forming part thereof.

Figure 1 is a side elevational view of a camera support showing my new design.

Figure 2 is a front elevational view,
Figure 3 is a rear elevational view, and
Figure 4 is a top plan view thereof.

I claim:

The ornamental design for a camera support,
as shown.

NEIL J. CREEDON.
